UNITED STATES PATENT OFFICE.

SAMUEL McCOMB AND JAMES B. McCOMB, OF NEW YORK, N. Y.

CARPET-RENOVATING COMPOUND.

1,172,297.

Specification of Letters Patent. Patented Feb. 22, 1916.

No Drawing.

Application filed November 5, 1914. Serial No. 870,497.

To all whom it may concern:

Be it known that we, SAMUEL McCOMB, a citizen of the United States, and JAMES B. McCOMB, a subject of the King of England, both residing at New York, in the county of Bronx and State of New York, have invented a new and useful Carpet-Renovating Compound, of which the following is a full, clear, and exact specification.

10 This invention relates to compounds for cleaning or renovating carpets and rugs, and has for its object to provide a compound of this kind which will save time and labor in cleaning such articles, and at the same time 15 preserve the carpet and leave it in a cleaner and sounder condition than when other carpet cleaning preparations are used.

Preparations of this kind heretofore produced are applied in a jelly or paste form 20 and must be scraped out and the carpet or rug then rinsed. This scraping and rinsing is avoided when our preparation is used, inasmuch as it does its work effectively with a light application and without even 25 saturating the carpet or rug, so that the time required for drying after other preparations are used is saved.

This compound works a chemical change 30 on the dirt, leaving it in powdered form to be swept off when dry. The carpet will then look like new, for the treatment will remove grease, fresh ink and other stains, will not cause the colors to run, and will leave the nap soft and pliable, restore the sheen and 35 eliminate all disagreeable odors besides acting as a moth preventive. Carpets or rugs may be treated with this preparation without even removing or taking them up from the floor, which is a matter of great convenience.

40 Our composition consists of the following ingredients, combined in the proportions stated:—

Neutral white soap, powdered	20	lbs.
Pure powdered borax	6	lbs.
45 Soda ash	3½	lbs.
Ultra marine blue, powdered	½	lb.
Glycerin	8	oz.
Pure oil of cedar leaves	3	oz.

In preparing the composition, the first four ingredients, which are in powdered form, are placed in a rotary mixer and the latter permitted to revolve very rapidly for about three minutes. The glycerin and oil of cedar leaves are then dropped in and the mixer allowed to rotate for another minute or so, or the whole process of mixing may be shortened into a space of time not exceeding three minutes. The rapid rotation of this machine mixes the ingredients uniformly and proportionately and leaves the mass in powdered form, free from paste or dough.

For use, 10 oz. of the above compound is dissolved in 4 gallons of hot water, and the resulting solution applied to the carpet or rug with a brush.

Having thus described our invention, what we claim as new and desire to secure by Letters Patent of the United States is:—

1. A compound in powdered form consisting of soap, borax, soda ash, ultra marine blue, glycerin and oil of cedar leaves.

2. A compound in powdered form consisting of the following ingredients in substantially the proportions named, viz: 20 lbs. of white soap, 6 lbs. of borax, 3½ lbs. of soda ash, ½ lb. of ultra marine blue, 8 oz. of glycerin and 3 oz. of oil of cedar leaves.
